GOLF CLUB HEAD

Toney Penna, Delray Beach, Fla., assignor to MacGregor Sport Products, Inc., Cincinnati, Ohio, a corporation of Ohio

Application July 30, 1956, Serial No. 42,442

Term of patent 14 years

(Cl. D34—5)

The dominant feature of the design resides in the configuration of the rear face of the golf club head.

I claim:

The ornamental design for a golf club head, substantially as shown and described.
